(57) **CLAIM**

The ornamental design for a flag, as shown and described.

DESCRIPTION

The patent or application file contains at least one drawing executed in color. Copies of this patent or patent application publication with color drawings will be provided by the Office upon request and payment of the necessary fee.

The sole FIGURE is a front elevation view of a flag, showing my new design, with the rear elevation view being a mirror image thereof.

The flag is flat and has no substantial thickness.

The thin black line shown along the perimeter of the flag represents the limits of the claim and forms no part of the claimed design.
